UNITED STATES PATENT OFFICE.

FRANK SOLEY, OF PHILADELPHIA, PENNSYLVANIA, ASSIGNOR TO MILLER LOCK CO.,
OF PHILADELPHIA, PENNSYLVANIA, A CORPORATION OF PENNSYLVANIA.

PADLOCK.

977,337.

Specification of Letters Patent. Patented Nov. 29, 1910.

Application filed May 11, 1910. Serial No. 560,635.

To all whom it may concern:

Be it known that I, FRANK SOLEY, a citizen of the United States, residing in Philadelphia, Pennsylvania, have invented certain 5 Improvements in Padlocks, of which the following is a specification.

The object of my invention is to construct a combination padlock in such a manner that the shackle will be held at both the heel and 10 the nose, and the combination mechanism will be distributed the moment the lock is closed.

The invention relates also to certain details of construction which will be fully described hereafter.

In the accompanying drawings:—Figure 1, is a perspective view of my improved combination padlock; Fig. 2, is a view of the lock with the rear casing removed, showing 20 the shackle in the closed position; Fig. 3, is a view similar to Fig. 2, with the tumblers of the lock removed and the shackle open; Fig. 4, is a sectional view on the line 4—4, Fig. 2; Fig. 5, is a detached perspective view of the 25 shackle; Fig. 6, is a detached perspective view showing the series of tumblers and washers; Fig. 7, is a detached perspective view of the cam plate; Fig. 8, is a perspective view of the dog; Fig. 9, is a perspective 30 view of the locking bolt; Fig. 10, is a perspective view of the device for throwing the dog out of engagement with the tumblers; Fig. 11, is a perspective view of the front 35 plate; Fig. 12, is a perspective view of the handle; and Fig. 13, is a view illustrating a modification of my invention.

A is the front casing of the lock and A' is the rear casing, secured together by rivets or other fastenings.

40 B is the shackle mounted on a pivot pin *a* secured to both sections of the case and this shackle has a nose *b* engaged by the bolt *C* pivoted at *c* to the casing. The bolt is made in the present instance from a plate; the engaging portion *c'* being turned at right angles to the body portion, as shown in Fig. 9.

D is the cam plate shaped as clearly shown in Fig. 7 and mounted on the sleeve carried by the stem *e* of the handle E. Pivoted to 50 a pin *d* of this cam plate is a dog F having a nose *f* which is adapted to enter the notches in the tumblers G and notches in the disk E' which is secured to the spindle *e*. Washers

H are mounted between the tumblers and secured to a post *a'* projecting from the casing, 55 so that, while the tumblers are free to turn, the washers are held in a fixed position. The first tumbler has a pin *g* which passes through slots *g'* in the other tumblers and into one of the slots *e'* in the disk E'. A 60 spring *f'* is mounted on the pivot pin *d* of the dog F and one end of this spring rests against the nose of the dog and the other rests against a pin *d'* on the cam plate D, tending to force the dog against the 65 tumblers. The cam plate D is recessed at *d''* for the passage of a post *a'*.

Mounted on a post *a''*, secured to the casing of the lock, is a spring I, one arm *i* of which rests against the casing and the other arm *i'* rests against a pin *d''* on the cam plate D, and the spring returns the cam plate to its normal position when the dog is released, as shown in Fig. 2. The bolt has a projection *c''* which bears against the portion *s* of 75 the cam plate, so that when the cam plate is turned on its pivot it will throw the bolt from the position illustrated in Fig. 2, to that illustrated in Fig. 3, releasing the shackle. When the cam plate is turned in 80 the opposite direction the portion *s'* strikes the bolt on the other side of its pivot, as illustrated in Fig. 3, and on the release of this cam plate its spring I will return it to its normal position and will cause the bolt 85 to be projected into the notch back of the nose of the shackle, as illustrated in Fig. 2. The surface *s''* of the cam plate rests in front of the heel *b'* of the shackle and locks the shackle in the closed position, so that the 90 shackle is doubly locked, namely, at the heel and at the nose.

When the cam plate is turned in the direction of the arrow, Fig. 3, to draw the bolt from the nose of the shackle, the edge *s''* 95 is moved out of the path of the heel of the shackle, so that the heel is released at the same time as the nose, consequently, the spring *k*, mounted on the pivot *a*, causes the shackle to spring open to the position 100 shown in Fig. 3.

Mounted on the pin *n* projecting from the case and through the opening *d''* in the cam plate is an arm N which is shaped to pass around the pivot of the tumblers and has a 105 tapered end *n'* which is adapted to engage

and force the nose of the dog F out of engagement with the tumblers as soon as the cam plate is released. A spring n^2 is attached to this arm and bears against the post a' . When the parts are in the locked position the dog is on one side of the point n' of the arm N, and when the cam plate is moved by operating the handle E the dog moves past this point and the point acts as a cam to force the dog out of the notches in the tumblers, immediately releasing the plate, which springs back to its normal position, as shown in Fig. 2. This movement destroys the combination.

15 I preferably secure a plate A^2 on the face of the casing, as shown in Figs. 1 and 11. This plate A^2 has the flange a^3 which incloses the inner portion a^2 of the handle, which is notched to form a part of the click mechanism. Surrounding this flange are the numerals, in the present instance arranged as the dial of a clock, but it will be understood that any number of numerals may be used, or letters, or other marks may be used in place of the numerals. There are as many notches in the surface e^2 of the handle as there are numbers on the dial, and on the casing are one or more projections with which these notched portions of the handle engage, so as to bring the handle in the proper position. On the handle is an arrow e^3 and a projecting portion e^4 , either one of which may be discarded, if desired.

By the above construction it will be seen that I can make a combination padlock in which the combination is destroyed as soon as the shackle is closed and locked, and that the shackle is held, not only at the nose, but also at the heel, making a very substantial, and at the same time a comparatively cheap, combination lock.

In Fig. 13, I have shown a modification of the invention in which the cam plate D', instead of being pivotally mounted, is mounted to slide in the casing, so that when it is in its raised position it will hold the bolt C' in the locked position and will engage the heel of the shackle B', and when depressed it will force the bolt out of engagement with the shackle and draw away from the heel.

The dog F' is in such position that on the rotary movement of the tumblers the plate will be drawn down through the medium of the dog and when the plate is raised the dog will be automatically thrown out by the pivoted arm.

I claim:

1. The combination in a padlock, of a casing, a shackle pivoted thereto, a cam plate, a bolt arranged to engage the shackle and to be actuated by the cam plate, a series of tumblers, a dog carried by the cam plate arranged to engage the tumblers, a spring actuated arm pivoted to the casing ar-

ranged to throw the dog out of engagement with the tumblers as the cam plate is shifted.

2. The combination in a padlock, of a casing, a shackle pivoted to the casing, a handle for operating the lock, a series of tumblers, a cam plate, a dog pivotally mounted on the cam plate and arranged to engage the tumblers, a bolt pivotally mounted in the casing and arranged to engage the nose of the shackle and to be acted upon by the cam plate, said shackle having a heel, the cam plate having a portion arranged to engage the heel when the shackle is closed, the plate being so proportioned that the heel will be released with the release of the nose of the shackle, and a spring actuated arm acting as a cam to force the dog out of engagement with the tumblers when the cam plate is shifted.

3. The combination in a padlock, of a casing, a shackle pivoted to the casing, a cam plate mounted within the casing, a pivoted bolt adapted to engage the nose of the shackle, the cam plate engaging the heel of the shackle and the bolt, a series of rotating tumblers, a handle arranged to rotate the tumblers, a dog pivoted to the plate and entering the notches in the tumblers, and a spring actuated arm pivoted to the casing and arranged to throw the dog out of the notches when the cam plate is moved so as to break the combination when the lock is closed.

4. The combination in a padlock, of a casing, a shackle pivoted thereto, a cam plate pivotally mounted in the casing, a pivoted bolt arranged to engage the nose of the shackle, a cam plate engaging the said bolt and the heel of the shackle, a pivoted dog on the cam plate, a pivoted arm for throwing the dog out of engagement with the tumblers, washers between the tumblers, a post carrying the washers extending through a slot in the cam plate, said post limiting the movement of the cam plate.

5. The combination in a padlock, of a casing, a shackle pivoted thereto, a cam plate pivotally mounted in the casing, a pivoted bolt arranged to engage the shackle and to be actuated by the cam plate as it is rotated, a series of tumblers, a dog carried by the cam plate and arranged to engage the tumblers, a spring actuated arm pivoted to the casing and arranged to throw the dog out of engagement with the tumblers as the cam plate is rotated in one direction.

6. The combination in a padlock, of a casing, a shackle pivoted to the casing, a cam plate pivotally mounted within the casing and a pivoted bolt arranged to engage the nose of the shackle when in a locked position, the cam plate engaging the heel of the shackle when in a locked position, tumblers, a dog carried by the cam plate and

arranged to engage the tumblers, means for actuating the tumblers and rotating the cam plate when the dog is in engagement with the actuating means, a spring for returning the cam plate to its normal position and means for throwing the dog out of engagement with the tumblers on the reversal of the movement of the cam plate.

In testimony whereof, I have signed my name to this specification, in the presence 10 of two subscribing witnesses.

FRANK SOLEY.
